(57) **CLAIM**

The ornamental design for a medical bidet, as shown and described.

DESCRIPTION

FIG. 1 is a perspective view of a medical bidet, showing my new design as secured in a commode.

FIG. 2 is an enlarged perspective view of the medical bidet of FIG. 1.

FIG. 3 is a top plan view of the medical bidet of FIG. 2.

FIG. 4 is a bottom plan view thereof.

FIG. 5 is a front elevational view thereof.

FIG. 6 is a rear elevational view thereof.

FIG. 7 is a left side view thereof.

FIG. 8 is a right side view thereof; and,

FIG. 9 is an exploded, perspective view of the medical bidet similar to FIG. 1.

In the drawings, the broken lines depicting the toilet are environmental subject matter only and form no part of the claimed design. The broken lines on the surfaces of the medical bidet illustrate portions of the article that form no part of the claimed design.
